(57) **CLAIM**

The ornamental design for a shoe, as shown and described.

DESCRIPTION

FIG. 1 is a top, front, right-side perspective view of a shoe; FIG. 2 is a bottom, left-side perspective view thereof;

FIG. 3 is a right-side view thereof;

FIG. 4 is a left-side view thereof;

FIG. 5 is a front view thereof;

FIG. 6 is a back view thereof;

FIG. 7 is a top view thereof; and,

FIG. 8 is a bottom view thereof.

The dashed broken lines depict portions of the shoe that form no part of the claimed design.

The claimed design includes the mirror images of the embodiment depicted that is not shown.

1 Claim, 8 Drawing Sheets
